PACKAGE OF TOY CONSTRUCTIONAL FIGURES

Simon Gompes and Herman Schpektor, both of Nieuwe Keizersgracht 58, Amsterdam, Netherlands

Filed Mar. 5, 1969, Ser. No. 16,069

Term of patent 14 years

Int. Cl. D9—04

U.S. Cl. D9—193

Fig. 1.

Fig. 2.

Fig. 3.

FIG. 1 is a plan view of a package of toy constructional figures, showing our new design;

FIG. 2 is a section on the line A—A of FIG. 1; and

FIG. 3 is an end elevational view of the package shown in FIG. 1.

We claim:

The ornamental design for a package of toy constructional figures, substantially as shown.
